ATTORNEY

UNITED STATES PATENT OFFICE.

FRANK H. SMITH AND THOMAS A. SINDELAR, OF CLEVELAND, OHIO, ASSIGNEES, BY
MESNE ASSIGNMENTS, TO BENDIX BRAKE COMPANY, OF CHICAGO, ILLINOIS, A
CORPORATION OF ILLINOIS.

MANUFACTURE OF BRAKE SHOES.

Application filed July 1, 1925. Serial No. 40,952.

To all whom it may concern:

Be it known that we, FRANK H. SMITH and THOMAS A. SINDELAR, citizens of the United States, residing in Cleveland, in the county of Cuyahoga, State of Ohio, have invented a certain new and useful Improvement in the Manufacture of Brake Shoes, of which the following is a specification.

This invention relates to the manufacture of brake shoes from pressed metal, the shoes illustrated being for an internal expanding automobile brake. An object of the invention is to form a shoe from relatively light metal without sacrificing its stiffness, by reinforcing it, preferably centrally of the shoe, by one or more radially-extending flanges integral with part of the cylindrical lining-supporting portion of the shoe. In one desirable arrangement there are two such flanges engaging each other centrally of the shoe.

Another feature of the invention relates to arranging a wear plate to be backed up centrally by the above-described central radial flanges, to transmit the force of the cam or other brake-applying means directly to the central web formed by the flanges.

Other objects and features of the invention, including a novel method of forming the described shoe, and various novel and desirable details of construction, will be apparent from the following description of the shoe shown in the accompanying drawings, in which:

Figure 1 is an elevation of part of a brake, showing two of the shoes with an operating cam arranged within a brake drum;

Figure 2 is a side elevation of one of the shoes on a larger scale;

Figure 3 is a plan view, approximately on the scale of Figure 1, of a blank for forming one of the shoes;

Figure 4 is a side elevation showing the first step in forming a shoe from the blank;

Figure 5 is a section on the line 5—5 of Figure 4, showing the channel cross-section of the stamping at this stage;

Figure 6 is a partial elevation looking from inside the shoe toward the left in Figure 2, and showing the mounting of the wear plate;

Figure 7 is a cross-section corresponding

to Figure 5, but on a larger scale, and showing the next step in forming the shoe; and

Figure 8 is a similar section through the finished shoe.

In the arrangement selected for illustration, the shoes 10, two of which appear in Figure 1, are arranged within a drum 12 and operated by a double cam 14 against the resistance of a spring 16. Suitable brake lining 17 (Fig. 2) is intended to face each shoe.

Each shoe is shown as a stamping formed from the blank appearing at 18 in Figure 3. As a first step, the blank is pressed into a curved channel-shaped member shown in Figures 4 and 5, having a central substantially cylindrical portion 20 and two side flanges 22. At the next step, flanges 22 are folded inwardly (Figure 7) to have each a cylindrical part 24 underlying the central part 20, and a substantially central radially extending flange 26. Finally the whole is heavily compressed into a T-section shoe, as shown in Figure 8, with parts 24 in engagement with part 20, and with flanges 26 in engagement with each other.

The various parts may be welded, or riveted, or otherwise secured in the positions shown in Figure 8. If desired, part 20 may be omitted, the shoe being then formed of two L-shaped stampings 24—26 arranged back to back and directly carrying the brake lining on parts 24, as explained in application No. 754,711, filed December 8th, 1924, by Adiel Y. Dodge, and directed to this improvement.

At one end an anchor fitting 28 may be riveted or welded or otherwise secured, preferably braced by a truss formed of triangular continuations 30 of flanges 26.

An important feature of the invention relates to welding or otherwise fastening in place a wear plate 32 bridging the ends of flanges 26 in such a manner as to transmit the thrust of cam 14 or its equivalent directly to the central web formed by the flanges. The wear plate shown has a central plane portion taking the thrust of the cam, and side flanges cut out for guiding engagement with the cam.

Hooks 34 for spring 16 may be provided in any desired manner.

While one particular shoe has been described in detail, it is not our intention to limit the scope of the invention to that particular shoe, or otherwise than by the terms 5 of the appended claims.

We claim:

1. A pressed metal brake shoe having a generally cylindrical lining-supporting part extending as a continuous unbroken portion 10 forming the friction face, and a pair of radially-extending reinforcing and stiffening flanges between the edges of said friction face and forming the sole stiffening means for the lining-supporting part.
15. 2. A pressed metal brake shoe T-shaped in cross-section and having a continuous and generally cylindrical lining-supporting part forming the friction face and a pair of radially-extending reinforcing and stiffening 20 flanges in engagement with each other and arranged between the edges of the friction face.
25. 3. A pressed metal brake shoe having a generally cylindrical lining-supporting part and a radial reinforcing web and including two parts substantially L-shaped in cross-section arranged in engagement back to back with their radial flanges jointly forming said web, and with the lining-supporting 30 part overlapping the outer flanges of the L-shaped parts.
35. 4. A T-section pressed metal brake shoe having a generally cylindrical lining-supporting part and a radial reinforcing web and including two parts substantially L-shaped in cross-section arranged in engagement back to back with their radial flanges jointly forming said web, and with the other flanges extending in opposite directions from said web and cylindrically curved and with the lining-supporting part forming 40 a double-thickness friction face.
45. 5. A shoe as defined by claim 4 having the cylindrical lining supporting part integral with the oppositely-extending cylindrically-curved flanges.
50. 6. A pressed metal brake shoe having a generally cylindrical lining-supporting part and a pair of radially-extending flanges forming the sole radial stiffening for the lining-supporting part, and having a wear plate at one end engaging and supported by said radial flanges.
55. 7. A T-section pressed metal brake shoe having a generally cylindrical lining-supporting part and a pair of radially-extending flanges between the edges of the cylindrical part and secured in engagement with each other to form a radial web, and having a wear plate at one end engaging and supported by said radial web.
60. 8. A T-section pressed metal brake shoe having a generally cylindrical lining-supporting part and a radial web formed of two radial flanges in engagement with each

other and integral with portions of the cylindrical part, and having a wear plate bridging across the ends of the radial flanges and supported thereby.

9. A T-section pressed metal brake shoe 70 having a generally cylindrical lining-supporting part and a radial web formed of two radial flanges in engagement with each other and integral with portions of the cylindrical part, in combination with a separate 75 wear member at the end of the shoe arranged to transmit thrust to both of the radial flanges.

10. A one piece pressed metal brake shoe 80 having a generally cylindrical lining-supporting part and a pair of radial flanges arranged inwardly from the edges of the cylindrical part and integral with portions of the cylindrical part and of a substantial depth to reinforce and stiffen the cylindrical part.

11. A one piece T-section pressed metal brake shoe having a generally cylindrical lining-supporting part and a radial flange arranged between the edges of the cylindrical part and integral with a portion of the cylindrical part and of a substantial depth to reinforce and stiffen the cylindrical part. 90

12. A T-section pressed metal brake shoe 95 having a generally cylindrical lining-supporting part and a radial flange arranged between the edges of the cylindrical part and integral with a portion of the cylindrical part and of a substantial depth to reinforce and stiffen the cylindrical part, and a wear plate secured to and centrally braced by the end of said radial flange.

13. A pressed metal brake shoe having a generally cylindrical lining supporting part and a pair of radial flanges integral with portions of the cylindrical part and of a substantial depth to reinforce and stiffen the cylindrical part, and a wear plate bridging across and braced by the ends of said radial flanges 105 and transmitting thrust to both of the flanges.

14. A pressed metal brake shoe having a generally cylindrical part and a pair of radial flanges of a substantial depth to reinforce and stiffen the cylindrical part, and a wear member arranged to transmit thrust to the ends of both of said flang 110.

15. A pressed metal brake shoe having a generally cylindrical lining-supporting part consisting of an outer part and integral flanges folded thereunder at opposite sides and continued as radial reinforcing and stiffening flanges of substantial depth, the body of the shoe being all in one piece. 112

16. A pressed metal brake shoe having a generally cylindrical lining-supporting part consisting of an outer part and integral flanges engaging each other and forming radial reinforcing and stiffening flanges of 118

substantial depth, the body of the shoe being all in one piece.

17. That method of forming a T-section brake shoe of pressed metal which comprises (1) pressing the metal to form a cylindrically-curved member channel-shaped in cross-section, and then (2) pressing the side flanges toward each other to press parts

of them against the bottom of the channel and other parts into engagement with each other to form a central web.

In testimony whereof we have hereunto signed our names.

FRANK H. SMITH.

THOMAS A. SINDELAR.
